UNITED STATES PATENT OFFICE.

JOHN E. STRIELTELMEIER, OF CINCINNATI, OHIO, ASSIGNOR TO THE IDEAL WHEEL COMPANY, OF CINCINNATI, OHIO, A CORPORATION OF OHIO.

KNOCKDOWN WHEEL.

1,079,305.

Specification of Letters Patent. Patented Nov. 18, 1913.

Application filed March 10, 1913. Serial No. 753,347.

To all whom it may concern:

Be it known that I, JOHN E. STRIELTELMEIER, a citizen of the United States, residing at Cincinnati, in the county of Hamilton and State of Ohio, have invented certain new and useful Improvements in Knock-down Wheels, of which the following is a specification.

This invention relates to improvement in construction of wheels, and it deals more especially with the type of wheels having resilient spokes.

One object within the contemplation of this invention is to render available an improved formation of the outermost extremity of the spoke elements, whereby the same have a uniform or continuous effective seating surface at the point of attachment to the rim, notwithstanding slight irregularities in the contacting elements, to the end that fracture strains will not be engendered by the clamping pressures, thus reducing the liability of breakage to a minimum.

Another object is to create a clamping structure of a very simple nature and composed of but few parts, whereby the spring elements will be very effectively secured to the rim, while preferably enabling said elements to be detached readily should a replacement thereof be occasioned by spring breakage.

Another object is to devise a means, whereby a wheel structure embodying spring spokes of the character and relationship defined by my copending application, Serial No. 720,521, may enable the adjacent springs of each adjacent spoke to radiate from the hub, while spaced apart a slight distance just permitting a polishing fabric to be inserted therebetween for the purpose of removing grit and keeping the parts clean.

This invention also proposes a fastening arrangement for the springs at the hub, which will be composed of but few parts permitting operation in a simple yet positive manner by nuts or the like to promote the demounting or assembling of individual spokes.

Another object is to devise a hub construction suitable for a wheel of the nature disclosed, and which will consist of a hub-structure adapted to be permanently retained on the axle, and a coöperating de-

tachable hub-structure of a very simple nature, forming essentially a demountable wheel-hub adapted to be received in interfitting relation upon the axle hub-structure and enabled to be secured thereto by a positive acting single element.

Another object is to devise a wheel construction that will be composed throughout of relatively few elements, each simple in design and so formed as to be capable of being inexpensively manufactured, and each so related to the others that they may be readily assembled to form a durable and well-organized wheel.

Other objects will be in part indicated in the following description, and in part rendered obvious therefrom in connection with the accompanying drawings.

This invention accordingly consists in the features of construction, arrangement of parts, and relations of elements, all as herein more particularly described, and in the extent of modification and range of equivalency indicated by the accompanying claims.

To adequately disclose this invention to those skilled in this art, it will suffice to expose the underlying essentials by way of one embodiment thereof, and to that end drawings of the form now preferred have been annexed and will be described in detail, and in such drawings like characters of reference denote corresponding parts throughout all the views, of which:

Figure 1 is a side elevation partly in section, showing one complete spoke in its relationship to the other features of the wheel construction. Fig. 2 is a section along a radial axial plane indicated by 2—2 of Fig. 1, showing further features. Fig. 3 is a perspective of an isolated clip such as is used in securing the springs to the demountable hub through the agency of a clamping block. Fig. 4 is a fragmentary perspective, showing the construction of the demountable hub. Fig. 5 is a top plan view of the hub of the wheel with all elements in place save the springs, but with the retaining collar not screwed up tightly.

Continuing now by way of a more detailed description of the parts of construction and essential characteristics of this invention, it is to be observed that while the following description will in many specific

respects refer solely to the annexed drawings, it is to be understood that the same is employed in an explanatory sense, and not for the purpose of limiting the invention to every specific feature enumerated.

The claims herein made are in part based on structural improvements growing out of and requiring conjoint use with the inventions disclosed and claimed in my copending applications Serial Nos. 720,521 and 734,128; and in part are also based on features capable of use independently of said inventions.

Referring now to Figs. 1 and 2, numeral 1 indicates a wheel-hub which, as here shown, has a ball-bearing or other anti-friction mounting on the axle 2, on which it is ordinarily permanently retained by means of the nut 3 inclosed by the hub-cap 4. It will, of course, be understood that the axle-hub 1 may be permanently keyed to a revolving axle in the case that the wheel is a propelling wheel instead of a steering wheel. The axle-hub member 1 is provided with a tapered periphery 5, which may be provided with facets, but which is preferably smooth and circular, as indicated by the drawings. A flange 6 rises, preferably radially, from a rear portion of the conical periphery 5, and is provided with a spaced series of apertures 7 that function to prevent the surmounting wheel-hub member from rotating relative to the hub member 1. The demountable wheel hub structure comprises a base member 8 having an annular shape, and having its inner periphery beveled at an angle corresponding with that of the beveled outer periphery 5 of the axle-hub member 1. This enables the respective members to telescope freely and to come to a snug tight fit in the final position. Rising from the rear edge of the member 8 is an integral annular flange 9 that terminates in an overhanging annular lip 10, preferably provided with a spaced series of notches 11, and having an under-beveled face 12. This flange 9 also has a spaced series of apertures 13 for receiving the shanks of bolts 14 having heads 15 that interfit in the notches 7 of the flange 6. These bolts in this arrangement have a two-fold function. *i. e.* first, to retain the spokes on the wheel-hub, and second, to prevent the wheel hub from slipping around the axle hub, which latter is accomplished by reason of the interfitting of the heads 15 of the bolts in the spaced apertures 7 in the flange 6.

By the construction herein proposed, the inturned flanges or feet of the springs are arranged to find a bearing radially outside of the bolts 14, *i. e.*, at a greater distance from the center of the wheel. As a matter of structural convenience, this is attained by means of an annular platform 16, which is L-shaped in cross section, and rests at

one end on a small shoulder projecting from the flange 9 of the wheel-hub member 8, and it has an annular flange 17 seated on the outer circumferential margin of said wheel-hub member 8; said flange having a series of apertures 18, through which the bolts 14 project.

The resilient spokes proposed by this invention are petal-shaped, and are preferably designed in accordance with the disclosures of my aforesaid application, Serial No. 720,521, and preferably each spoke is formed of two springs 19 and 20, arranged in converse symmetrical relation to the bisecting radius of the spoke. These spring sections enter the hub along radius lines and have portions bent in a circumferential direction, and which preferably terminate near the center line of each spoke. As indicated by 21, these foot-like flanges are supported directly upon filling strips 22, which may be constructed of a softer metal than the steel used in the springs, such as brass or copper. These filling strips 22 are shaped like a shallow channel-bar, so that their marginal portions will extend radially for a short distance and constitute spacers for keeping the adjacent back-to-back spring spaced slightly apart at the hub, as shown by Fig. 1, to permit the insertion of a cleaning or polishing fabric. It is to be understood that while these filling strips 22 may be formed integral with a part of the wheel-hub, such as the annular platform 16, nevertheless, they are preferably in the form of separate pieces since thereby the parts are given a somewhat greater degree of latitude, or self-adjustment to equalize strains when the clamping elements are tightened.

A clamping plate 23 having its ends beveled and in shape conforming to a section of a hollow cylinder, is arranged to overlie and rest directly upon the inturned flanges or feet 21 of the springs. A filler 24 of relatively soft material such as brass, fiber or the like, may line the inner face of each clamping plate 23. The inner beveled end of each clamping plate takes under the beveled flange 10, and its outer beveled end is engaged by the under-beveled lip 25 projecting from the clip 26, which is preferably sector-like in shape and has an aperture 27 through its body portion and through which the projecting end of the bolt 14 may pass. The lip 25 is sufficiently wide circumferentially to completely fill the space between the springs 19 and 20 of each spoke at the hub, and it will be noticed that such lip is narrower than the body portion of the clip, leaving open notches 28 for receiving the edges of the springs. The edges of the springs also preferably enter the notches 11 provided by the annular flange 10, and in this way the springs are

positively restrained against creeping relative to the wheel-hub to which they are secured.

To hold the wheel hub as a unit demountably on the axle-hub, an annular follower 29 is screw-threaded at 30 to the axle hub member 1, and has an overhanging annular flange 31 adapted to abut some portion of the wheel hub, preferably the beveled edges 10 32 of the clips 26, and thereby hold the wheel-hub in place. By this arrangement, the series of nuts 33 which individually secure the clips in place are inclosed against mud; the entire hub has a smooth finished 15 appearance free from projections, and yet either the wheel as a unit may be demounted, or one or more spoke springs replaced in case of breakage.

When the clamping plates 23 are drawn 20 downwardly or inwardly toward the axis they not only bind the springs tightly in place by means of their feet, but they also exert pressure laterally, *i. e.*, in a circumferential direction, and force the spoke 25 springs sidewise against the spacing material intervening therebetween, thus resulting in a very compact and rigid hub construction.

It will be perceived that the means proposed for attaching the resilient spokes to the rim may be used whether said spokes are formed of two radial spring portions which meet together in overlapping ends at 30 the rim, or whether the spokes are formed 35 of two radial spring portions that extend continuously in an unbroken connection around the attaching loop, as in the case of a spoke formed of a single spring bent into the shape shown by the drawings and having its ends butt together at the hub. Preferably, however, each spoke will be formed of two separate springs, each secured at the rim and hub respectively, since in this way it is somewhat easier to manufacture the 40 springs, to temper them, and they may be carried more compactly and replaced with less waste of material in case of fracture.

Tests under working conditions show that springs of the character herein specified 50 play a greater tendency to crystallization and fracture at or adjacent their point of attachment to the rim than elsewhere. The causes for this are rather profound, but I have succeeded in effecting a very simple 55 improvement that better overcomes these difficulties than anything heretofore known to me. The one spring 19 has its end rounded off in a progressive curve free from sharp deflections, said curve being concaved toward the wheel axis and terminating in a 60 slightly projecting portion 34 that reinforces the contacting portions of the adjacent spring 20 at the point of deflection adjacent the retaining clamping plate at the 65 rim. The adjacent spoke spring 20 has its

end curved convexedly outward so as to overlap and closely fit about the adjacent portions of the adjacent spoke spring 19. The overlapping portion of the spring 20 externally seats into a correspondingly shaped recess in the rim 35 of the wheel, and such recess is preferably lined with brass or fiber, as indicated by 36 to provide a better seating surface.

The clamping device here proposed consists of two L-shaped parallel movement clips, the one having its foot disposed along the rear edge of the rim, and its leg on the outer periphery of the rim, and the other arranged conversely. The first-mentioned clip is preferably permanently secured to the rim, and is here indicated by 37, and it comprises a radial portion 38 that extends toward the axis along the inner side of the rim, and it terminates in an outwardly turned flange 39, providing an under-beveled face 40. The permanent clip 37 also provides, preferably, a portion 41 that is countersunk in the outer periphery of the rim, and extends toward the front side thereof and at its front extremity it provides a beveled face 42 in parallelism with the aforesaid beveled face 40. The desired angularity of this face may be secured in a very simple manner by turning down the end portion of the clip 37 in the way shown, so that such portion also tends to lock the clip against detachment relative to the rim.

The coöperating detachable clip is indicated by 43, and it comprises a portion constituting a clamping-plate 44 terminating in a beveled end adapted to coact with the under bevel of the flange 39, and it also embodies a side portion 45 terminating in an under-beveled lip 46 adapted to coact with the beveled surface 42. It will be perceived that the detachable clip 43 is freely separable by a movement away from the wheel transversely to the plane thereof, and that if it be forced in the opposite direction it will move in parallelism with the layers of springs so as to clamp the latter with a uniform pressure. This movement is secured by means of a bolt 47 that passes through an aperture in the non-removable clip, then through an aperture in the rim and its free end projects through an elongated aperture in the portion 45 of the detachable clip. A nut 48, which it will be perceived is very accessible to the user, exerts pressure on the detachable clip 43 and urges it securely into its clamping position, and by reason of the fact that the aperture in said clip is elongated in a radial direction, there will be no binding or interference between the shank of the bolt and the detachable clip.

It will thus be perceived that this invention is well adapted to achieve the objects and advantages recited in the foregoing, and

of doing so in an exceedingly simple manner.

In the light of this disclosure, those skilled in mechanical arts will be enabled 5 to utilize matters of current knowledge in modifying details of this invention and in adapting the same to meet the requirements of various circumstances, without however departing from the features and combinations which from the aspect of the prior art 10 will be found to constitute true characteristics of this invention, and such constructions are therefore to be regarded as falling within the scope or range of equivalency of the 15 following claims.

Having thus described my invention, I claim as new and desire to secure by Letters Patent of the United States:—

1. A resilient wheel of the nature disclosed 20 combining a hub, a plurality of looped flat-spring spokes radiating from said hub, a rim providing seating surfaces for the extremities of said spokes, a member secured to said rim providing a pair of parallel beveled faces, the one being adjacent the back edge of the inner periphery, and the other being adjacent the front edge of the outer periphery of said rim, and a cooperating L-shaped clip having beveled 25 faces engaging those above mentioned, whereby said clip will move in parallelism with said member to clamp its associated spoke to said rim.

2. A resilient wheel of the nature disclosed 30 combining a rim, an L-shaped member permanently secured thereto, a detachable L-shaped member arranged conversely to the former, to form an open rectangle, inclosing a section of the rim, a flat spring 35 forming a spoke element also inclosed within said open rectangle, and means for drawing said two members together to clamp said spring flat-wise against said rim.

3. A resilient wheel of the nature disclosed 40 combining a rim, means providing parallel beveled surfaces at diagonally opposite points of a transverse section of said rim, a flat spring having a portion seated flat-wise on said rim, a member having beveled faces coacting with the aforesaid beveled surfaces and providing a portion for clamping said spring to said rim, and screw-threaded means for moving said member laterally relatively to said rim whereby it 45 will be forced into clamping relations with said spring by said beveled faces.

4. A resilient wheel of the nature disclosed 50 combining a rim, a member extending radially inward along the back side of said rim and providing at the inner periphery of said rim a lip having an under-beveled face, an L-shaped clip having a portion 55 extending parallel with the axle of said wheel, and terminating in a beveled end engaging said lip, said portion bending at

right angles and extending along the front side of said rim and terminating in a beveled face contacting a correspondingly beveled surface provided by said rim, a flat metal spoke element engaged by said clip and 60 means for drawing said parts together.

5. A resilient wheel of the nature disclosed 65 combining a hub, a rim, an equispaced plurality of loop-like spokes each providing spring portions having concaved faces and convexed backs, said portions being spaced widely apart face-to-face, but spaced only slightly apart back-to-back, and having flange-like feet extending toward one another on the periphery of the hub, a radially movable clamping-block resting on 70 said feet between the corresponding spring portions, spacers alternating in succession with said clamping-blocks around the periphery of said hub to separate the same, 75 and means for drawing the clamping-blocks radially inward to coöperate with said hub in clamping said flange-like feet.

6. A resilient wheel combining a hub, a rim, a plurality of loop-like spokes each 80 providing conversely arranged spring portions having concaved faces having retaining flanges and spaced widely apart face-to-face but only a slight distance apart back-to-back, spacers contacting between the back-to-back portions, movable clamping blocks between the face-to-face portions and co-operating with said flanges, and means for moving said clamping-blocks relatively to 85 said hub, to bind said portions in place.

7. A resilient wheel of the nature disclosed 90 combining an axle hub having an annular flange provided with a circumferentially spaced series of sockets in the side wall thereof, a wheel hub adapted to telescope the axle hub and having a series of bolts extending transversely therethrough, and having their heads adapted to enter 95 said sockets to prevent said wheel hub from turning relatively to said axle hub, a plurality of springs of sheet-metal disposed edgewise to the plane of the wheel radiating from said wheel hub forming spokes for the wheel, means for attaching said spokes to said wheel hub through the agency 100 of said bolts, and means for retaining said wheel hub against axial movement on said axle hub.

8. A resilient wheel of the nature disclosed 105 combining an axle hub having an annular flange provided with a circumferentially spaced series of sockets in the side wall thereof, a wheel hub adapted to telescope the axle hub and having a series of bolts extending transversely therethrough, 110 and having their heads adapted to enter said sockets to prevent said wheel hub from turning relatively to said axle hub, a plurality of springs radiating from said wheel hub forming spokes for the wheel, means 115 for retaining said wheel hub against axial movement on said axle hub.

120

- for attaching said spokes to said wheel hub through the agency of said bolts, and a collar having a screw-threaded mounting on said axle hub adapted to bear against the outer side of said wheel hub and obstruct its removal from said axle hub.
9. A resilient wheel of the nature disclosed combining an axle hub having an annular flange provided with a circumferentially spaced series of sockets in the side wall thereof, a wheel hub adapted to telescope the axle hub and having a series of bolts extending transversely therethrough, and having their heads adapted to enter said sockets to prevent said wheel hub from turning relatively to said axle hub, a plurality of springs radiating from said wheel hub forming spokes for the wheel, means for attaching said springs to said wheel hub, nuts threaded to said bolts for operating said means, and a collar mounted on said axle hub adapted to prevent axial relative movement of said wheel hub and having an annular recess in its inner side adapted to conceal said nuts.
10. A resilient wheel of the nature disclosed combining an annular hub having at one end an annular flange providing an under-beveled surface, and having an aperture in its side wall, a bolt passing through said aperture parallel with the axis of said hub, a spring-seating member arranged at a greater radial distance from the hub axis than said bolt, a flat spring arranged edge-wise to the plane of the wheel and having an inturned foot-like portion seated on said member, a clamping-block having beveled ends engaged at one end by said hub flange, and a clip adapted to be urged by pressure derived from said bolt to engage the other end of said clamping-plate and retain said spring by means of its foot-like portion.
11. A resilient wheel of the nature disclosed combining a hub member having at one end an uprising annular flange having a perforation in its side wall and providing an under-beveled surface, a bolt extending parallel with the axis and engaging said hub member through said perforation, a spring-seating peripheral surface being provided at a greater radial distance from the axis than said bolt, a flat spring having an inturned foot-like extension seated on said peripheral surface, a clamping-plate overlying said foot-like portion and having one end engaged by said flange, and means for engaging the other end of said clamping plate and adapted to clamp the same by pressures derived from said bolt.
12. A resilient wheel of the nature disclosed combining a hub-member providing an external periphery and a flange at one end uprising beyond said periphery and providing an under beveled surface, a bolt extending parallel with the axis of said hub
- radially nearer the axis than the said periphery of said hub, a flat spring having an inturned foot-like portion seated on said periphery, a clamping-plate engaged at one end by said flange and overlying said foot-like portion, and a clip retained by said bolt adapted to bear against the other end of said clamping-plate to retain the same in clamping relation with said spring.
13. A resilient wheel of the nature disclosed combining a hub, a rim, and an equi-spaced series of loop-like composite spokes all radiating in the same plane and each consisting of homologous forward and rear portions formed of wide sheet metal conversely arranged edgewise to the plane of the wheel, and rigidly clamped to the hub at points widely separated circumferentially whereby each spoke has a base wide both peripherally and axially, said portions emerging from the hub along a radius line and immediately progressively curving away from said radius line toward the center-line of their spoke, said loop-like spokes being slightly separated from one another at the hub to form narrow spaces between the rear radial portion of each loop-like spoke and the forward radial portion of the following loop-like spoke, spacers in said narrow spaces, clamping blocks between the widely separated portions, and means operative independently of said spacers for securing said clamping blocks to said hub.
14. A wheel of the nature disclosed combining a hub-member, a spaced series of flat spoke springs arranged edgewise to the plane of the wheel and having concaved faces spaced widely apart but separated back-to-back only a relatively slight distance, spacers interposed between the back-to-back springs, a series of blocks alternating with said spacers and each arranged between two face-to-face springs, and adjustable means for engaging the extremities of said blocks and adapted adjustably to close said blocks toward the center of the hub whereby clamping pressures may be exerted on the two springs and the intervening spaces between each two blocks taken in succession.
15. A resilient wheel of the nature disclosed combining an inner hub-member, a telescoping outer hub-member, a series of resilient spoke elements radiating from said outer hub-member, a series of clamping blocks detachably securing said spoke elements to said outer hub, a retaining member secured to said inner hub member and simultaneously engaging all of said clamping blocks and also serving to restrain axial movement of said outer hub-member on said inner hub-member, and a rim to which said spoke elements are secured.
16. A resilient wheel combining a rim, and a hub, a detachable L-shaped member having one leg extending in an axial direction over

- the periphery of one of said parts and having its other leg extending radially along the side of said part, an element projecting from the other side of said part, and having 5 a wedge-engagement with the one leg of said member, the other leg of said member having a wedge engagement at the first mentioned side of said part, means for translating said L-shaped member whereby it may 10 have a parallel clamping movement, and a flat spring extending between the one leg of said member and the periphery of said part, whereby it may be clamped thereto.
17. A spring wheel of the nature disclosed 15 combining a hub, a felly, a clip comprising a cross-bar portion arranged transversely to the plane of the wheel and an integral side portion formed at right angles to the cross-bar portion and extending at one side of and 20 parallel with the median plane of the wheel, a loop-like spoke of spring metal having a forward and a rearward strip curved to present concaved faces opposite each other and entering between said clip and felly from 25 opposite directions and interfitting in overlapping relation with one another, a bolt securing the side portion of said clip to the felly, and means for securing said strips at widely spaced points to the hub.
- 30 18. A spring-wheel of the nature disclosed combining a hub having screw threads 30 adjacent one end, a plate 9 adjacent the other end, a movable part 26, a wedge-block 23 intervening between said plate and said 35 part, a bolt 14 extending in an axial direction from said plate into said part, a member 29 engaging said hub screw-threads and bearing laterally against said part, a felly, and resilient flat strips extending along opposite sides of said wedge-block and curving 40 to meet the felly radially opposite the same and forming a loop-like spring-spoke.
19. A wheel of the nature disclosed combining a felly, a series of sheet-metal spring 45 spoke-elements, a hub-member providing a flange 9 rigid therewith having a series of equi-spaced notches 11 extending radially and adapted to receive radial portions of the spoke-elements, a separable part 23 adapted 50 to intervene between each pair of separated spoke elements to space the same, said part providing a face flush with the wall of one of said notches and keyed against rotation on said hub-member by the coaction of 55 said spoke elements with the walls of said notches, and a member 26 detachably mounted with relation to the hub adapted to retain said separable part against displacement in an axial direction.
- 60 20. A wheel of the nature disclosed combining a felly, a hub-member having an overhanging flange provided with series of radial slots, two resilient sheet metal spoke elements arranged back-to-back emerging 65 radially from a close fitting relation with said slots and then curving apart and connected to the felly at points radially midway said slots, and wedge means for engaging said spoke elements and drawing the same radially inward into firm seating relation with said hub-member.
21. A wheel of the nature disclosed combining a felly, a hub having a shoulder 6, a spoke-seating member concentric therewith in end abutment with said shoulder and 70 having a series of radial slots 11, each adapted to accommodate two spoke elements, a pair of resilient sheet-metal spoke elements 75 radially emerging from each slot and curving apart and each meeting the felly at a point radially midway its slot and the adjacent one, a hub and providing a conical wedge-seat 32, jacent one, a ring 29 screw threaded to said hub and means for utilizing said wedge-seat for maintaining the position of said hub member 85 and simultaneously wedging said spoke elements radially toward said hub.
22. A wheel of the nature disclosed combining a felly, a hub having a shoulder 6, a spoke-seating member concentric therewith 90 in end abutment with said shoulder and having a series of radial slots 11 each adapted to accommodate two spoke elements, a pair of resilient sheet-metal spoke elements radially emerging from each slot and curving apart 95 and each meeting the felly at a point radially midway its slots and the adjacent one, means for wedging said spoke-elements in rigid relation with said spoke-seating member, and bolts coöperating with said shoulder and passing in an axial direction 100 through said member to operate said means.
23. A wheel of the nature disclosed combining a felly, a hub having a shoulder 6, a spoke-seating member 8 mounted thereon 105 and restrained against endwise movement in one direction by said shoulder, said member providing a series of radial slots 11, a resilient sheet-metal spoke element radially emerging from each slot and curving backwardly to meet the rim at a point radially midway its slot and the next adjacent slot, a part 26 arranged at the outer end of said member and providing an under wedge-surface 25, a bolt for drawing said part toward 110 said member in an axial direction, and means for utilizing said wedge-seat for wedging said spoke elements radially toward 115 said hub.
24. A wheel of the nature disclosed combining a felly, a hub-member 8 having a radially projecting annular flange 9 providing a series of radial slots, sheet-metal resilient spoke elements having radial portions emerging from said slots and curving into 120 a connection with said felly, means 23 for spacing said elements arranged at one side of said shoulder and providing spaces in 125

registry with said slots and receiving adjacent radial portions of said spoke-elements and keyed thereby against rotation, means arranged on the side of said first-mentioned 5 means remote from said flange operating to position said first means and providing a beveled face 25 adapted to produce clamping pressures effective to retain said spoke elements against outward movement, and a 10 bolt extending in an axial direction through said flange and engaging said last mentioned means.

25. A wheel of the nature disclosed combining a felly, a hub-member, an annular 15 plate 9 having an inturned wedge-like projection 10 provided at one side of said hub-member, a complementary part 26 arranged at the other side of said hub-member and having a wedge-like projection 25 directed 20 toward said plate but separated therefrom, an annulus 16 seated on said hub-member between said plate and part and adapted to constitute a spoke-seating element, a series 25 of loop-like spokes formed of spring metal strips radiating from said annulus, means for utilizing said wedge-like projections for retaining said strips in seating relation with said annulus, and a bolt extending in an axial direction through said plate, annulus, and part and adapted to clamp them together.

In testimony whereof, I have hereunto set my hand.

JOHN E. STRIETELMEIER.

said annulus, and adjustable means for drawing said part toward said plate.

26. A wheel of the nature disclosed combining a felly, a hub-member, an annular plate 9 having an inturned wedge-like projection 10 provided at one side of said hub-member, a complementary part 26 arranged at the other side of said hub-member and having a wedge-like projection 25 directed toward said plate but separated therefrom, an annulus 16 seated on said hub-member between said plate and part and adapted to constitute a spoke-seating element, a series 40 of loop-like spokes formed of spring metal strips radiating from said annulus, means for utilizing said wedge-like projections for retaining said strips in seating relation with said annulus, and a bolt extending in an 45 axial direction through said plate, annulus, and part and adapted to clamp them together.
